CONTAINER

Gordon Leonard, Kansas City, Mo.

Application March 16, 1949, Serial No. 81,737

2 Claims. (Cl. 229—17)

1

This invention relates to a container adapted to be formed of paper or similar material and used in packaging milk or other liquid products.

Containers of this character are usually sealed after filling and have pour openings normally covered by a tear flap which is torn loose by starting the tear with the finger nail or other instrument when the contents are to be dispensed. Starting of the tear is often difficult because the adhesive required in forming a sanitary seal about the opening seals the tear flap and it is difficult to raise the flap. This difficulty has been overcome in part by providing the material from which the tear flap is formed with a cut-out portion, but these cut-out portions are difficult to handle when manufacturing the blanks from which the containers are formed.

Another difficulty is that the adhesive spreads over the partial cut which defines the pour opening and when the flap is torn loose the edges of the pour opening present irregular and uneven surfaces that make clean pouring difficult.

It is, therefore, the principal purpose of the present invention to provide a container of this character having a pour opening covered with a tear flap that is secured by an adhesive which completely surrounds the pour opening without interference with removal of the inner closure and in which the tear flap has a free and unattached edge that is readily engaged and pried up by the finger nail or other instrument into a position to be gripped between the thumb and finger in completing the tear.

It is a further object of the invention to provide a container having the side wall or walls and top formed of a single sheet of material of a shape to provide a relatively wide vertical seam and overlapping portions which contain the pour opening and the tear flap respectively.

A further object of the invention is to provide a container having a relatively narrow vertical seam at the base and which widens at the top to provide the overlapping portions extending substantially across the entire top of the container, thereby providing a closure fold having uniform thickness across the entire length of the seal.

A further object of the invention is to provide a container having the above features which may be formed of a minimum of material.

It is also an object of the invention to provide an inexpensive pre-formed container which may be made available for practicable use by small dairies and other liquid packaging concerns.

In accomplishing these and other objects of the invention hereinafter pointed out, improved

2

structure is provided, the preferred forms of which are illustrated in the accompanying drawings wherein:

Fig. 1 is a perspective view of one form of container constructed in accordance with the present invention and showing the top thereof in folded and sealed condition to contain a liquid such as milk.

Fig. 2 is a perspective view of the container showing the top thereof open and prior to sealing thereof.

Fig. 3 is a perspective phantom view of the sealed container to illustrate the sealing portions and areas of application of the adhesive, the tear flap being torn back to expose the pour opening.

Fig. 4 is a perspective view of another form of container constructed in accordance with the present invention.

Fig. 5 is a phantom view of the container illustrated in Fig. 4 and particularly showing the location of the adhesive areas.

Fig. 6 is a perspective view of the upper portion of the container showing the closure disk and tear flap opened to expose the pour opening.

Fig. 7 is a fragmentary sectional view through the bottom of the container on the line 7—7 of Fig. 4.

Fig. 8 is a plan view of two adjacent blanks as stamped from a web of material to form the container illustrated in Figs. 1 to 3, inclusive.

Fig. 9 is a similar view of blanks forming the container illustrated in Figs. 4 to 7, inclusive.

Referring more in detail to the drawings and first to the form of the invention illustrated in Figs. 1 to 3, inclusive:

1 designates one form of container constructed in accordance with the present invention and which is especially adapted for packaging milk or other liquid from which the contents may be drunk directly therefrom. The body 2 of the container is rolled from a blank 3 that is adapted to be stamped from a web of material 4 such as paper or the like. The blank 3 when cut from the web has an arcuate edge 5 of a length to provide the desired circumference at the base of the container and an overlap portion 6. The side edges 7 and 8 of the blank extend substantially radially with respect to the center of curvature of the arcuate edge 5 so that the container formed from the blank tapers upwardly and outwardly to permit nesting of the containers prior to use.

The edges 7 and 8 terminate substantially midway of the height of the blank in edge portions 9 and 10 diverging at a greater angle than the edge portions 7 and 8 to provide wings 11 and

11' at the upper portion of the blank, the side edges 12 and 13 of which are preferably formed on radii conforming to the center of curvature of the edge 5. The midportion of the blank has a relatively straight edge 14 which extends parallel with a tangent of the arcuate edge 5 and which is of sufficient length to provide one side of the top of the container as defined by lines of score 15 and 16 extending inwardly of the blank and terminating in oppositely directed scores or lines of fold 17 and 18 located in registry with the points of juncture 19 and 20 of the side edges 12 and 13 with the diverging edge portions 9 and 10 as shown in Fig. 8.

The edges of the blank at the ends of the edge 15 portion 14 are shaped to provide slight peaks 21 and 22 and have a length substantially conforming to the length of the edge 14. Extending inwardly from each peak point 21 and 22 are radial scores 23 terminating in lateral scores 24-25 and diverging scores 26-27 substantially terminating at the ends of the scores or lines of fold 17 and 18. The end edge portions of the blank are offset outwardly as at 28 and 29 to provide fold flaps 30 and 31 substantially conforming to the length of the edge 14 for a purpose later described. The outer edges of the fold flaps 30 and 31 extend substantially parallel with tangents of the arcuate edge 5 and join with the edge portions 12 and 13 of the wings 10 and 11.

The inner portion of the fold flaps are defined by scores 32 and 33. Inset from the scores 32 and 33 and from the edge 14 are similar scores 34, 35 and 36 which register with ends of the scores 24 and 25 to provide sealing flaps 37, 38, 35 and 39 which cooperate with sealing flaps 40-41 and 42-43 on the respective sides of the scores 23. Radial scores 44 and 45 are also provided in registry with the offsets 28 and 29 to cooperate with the scores 15 and 16 in forming the corners 40 of the top of the container.

The ends 46 and 47 of the blank intermediate the edges 12 and 13 and the adjacent scores 44 and 45 are adapted to overlap and form a double thickness for one side of the carton top. The underlying portion 47 is provided with a transverse slot 48 to provide a pour opening, the ends of which terminate short of the fold line 45 and edge 13, respectively. The opposite or outer portion 46 has substantially parallel lines of perforations 49 and 49' extending inwardly from the edge 12 toward the score 44 to provide a tear flap portion 50 in overlying relation with the slot 48 when the blank is rolled to form the container.

The blanks thus described are stamped from the web 4 in reverse relation as illustrated in Fig. 8 so as to conserve the material and eliminate any cut-out portions intermediate the blanks that might interfere with operation of the dies.

The overlap forming the seam at the tear flap end of the blank is provided with a stripe of adhesive 51 terminating at the end of the edge 7 and which diverges into sealing stripes 52 and 53 that are joined by a transverse sealing stripe 54, the stripe 54 being spaced from the inner line of perforation 49 to provide a relatively narrow un-gummed area 55 therebetween. The adhesive stripe 53 continues along the fold line 44 as indicated at 56 to join with a transverse stripe 57 spaced from the line of perforation 49' to provide a relatively narrow unsealed area 58 corresponding to the area 55. The gum stripe 56 also continues along the offset 28 and joins with a stripe 59 that extends along the edge of the fold flaps

The transverse adhesive stripes 54, 57 and 59 extend to the edge 12 and the stripes 59 and 57 are interconnected along the edge 12 by a stripe of adhesive 60. Inset inwardly from the edge 12 and connecting the gum stripes 54 and 57 is a narrow gum stripe 61 that is also slightly offset from the outer end of the slot 48 when the blank is rolled to form the container.

In forming the container, the blank is rolled 10 into a substantially truncated cone form to bring the sealing stripes into contact with the opposite face of the other end of the blank to provide a leak-tight closure therefor.

Attention is directed to the fact that due to the inset of the sealing stripe 61, an unsealed area is provided to permit engagement of the edge portion 12 intermediate the lines of perforation by the finger nail or other instrument to lift the tear flap and effect tearing thereof along the lines of perforations when the pour slot is to be exposed. When the blank is rolled and sealed, the blank breaks on the lines of fold or scores 44, 15, 16 and 45 to provide a rectangular-shaped fill mouth 62 as shown in Fig. 2.

The bottom of the rolled blank is closed by a disk-like insert 63 that is inserted through the mouth 62 and which has a depending annular flange 64 that engages the inner face of the base of the container above an arcuate stripe of adhesive 65 applied along the arcuate edge 5 and which is adapted to seal therewith when the arcuate edge 5 is turned retractively along the inner face of the flange to form the base edge 66 of the container. The container may then be dipped, sprayed or otherwise coated with paraffin, plastic or other sealing material to close the perforations and further render the container leak-tight.

The containers thus described may be nested and packaged in nested condition for storage and shipment on order to the small dairyman or other packager of liquid products.

The container as illustrated in Fig. 2 may be filled by conventional filling machines and after filling the top is closed by breaking the sides inwardly on the scores or lines of fold 24, 25, 26, 27 and 23. Simultaneously with breaking of the sides on the fold lines, the front and back sides are drawn inwardly with the triangular portions intermediate the lines of fold 16-26, 27-45, 15-25 and 24-44 and bend on the lines of fold 15, 44, 16 and 45 to lie against the inner faces of the front and back portions while the sealing flap portions 40-41 and 42-43 are engaged between the sealing flap portions 37, 38 and 39 with the folds formed by the scores 34, 35 and 36 in abutting relation substantially midway the length of the outer seal flap. The projecting portion formed by the sealing flaps 30 and 31 (Fig. 2) is then turned inwardly over the seal flap 38, after which the folded seal flaps are sealed by applying heat along the fold and fusing the coating to form a leak-tight closure.

In operating the container the finger nail may be engaged under the free edge 12 intermediate the lines of perforations 49-49' so as to raise the undersealed portion sufficiently to be gripped between the thumb and finger, after which the tear flap 50 is drawn retractively and torn along the lines of perforation to expose the pour slot. The contents may then be drunk directly from the container or the contents poured through the slot 48. When thus opened, the unsealed area around the pour slot provides clean sanitary edges free of adhesive or torn surfaces.

is substantially the same as the form illustrated in Figs. 1 to 3 with the exception of the pour opening and the overlap forming the longitudinal seal of the container. In this form of the invention, the end edges 68 and 69 of the blank 70 diverge outwardly on substantially continuous lines from the arcuate base edge 71 of the blank as shown in Fig. 9. The portions 72, 73 and 74 of the blank forming the top closure are identical in shape and scoring with the first described form of the invention, however, the pour opening 75 and a closure 76 therefor are formed by the provision of an arcuate slot 77 having the ends spaced apart to leave a relatively narrow hinging portion 78 therebetween. The gum or adhesive 79 is applied along the arcuate edge 71 in the manner as described in the first form, however, the adhesive forming the vertical seam widens toward the upper end of the container and branches into space sealing stripes 80 and 81 that are connected by transverse gum stripes 82, 83 and 84, the stripes 82 and 83 being located on the respective sides of lines of perforation 85 and 86 forming a tear flap 87 which overlies the arcuate slit 77 forming the pouring opening. The stripes 82 and 83 are connected by a relatively narrow stripe of adhesive 88 that is inset inwardly from the outer side edge of the blank to provide an unattached finger-engaging area 89. In order to provide a larger unattached area 89, the edge of the blank may be provided with a tongue-like extension 90 that is cut from the opposite edge of the next adjacent blank as indicated at 91 (Fig. 9).

To facilitate tearing the outer terminals of the tab extension, the extension may be narrower than the width of the tear flap and the adjacent portions of the lines of perforations converge inwardly as indicated at 92 and 93 (Fig. 9).

The folding and formation of a container from the blank as illustrated in Fig. 9 is the same as in the first-described form of the invention, however, in this form the pour opening being relatively narrower than the elongated slit does not require the same width of seam. Consequently, the seam may be narrower and located intermediate the sides of the container as shown in Fig. 5. In order that the closure portion contained within the arcuate slot may be removed to provide a substantially circular opening, the portion of the blank contained within the arcuate slot is covered with adhesive 94 so as to adhere to the underside of the tear flap as shown in Fig. 5. After formation of the container it is coated with a wax or the like as previously described.

This form of the invention may be nested, packaged and stored in the same manner as the first described form and filled in similar manner, after which the top flaps are folded and sealed. When the tear flap 87 is to be torn loose to expose the pour opening, the finger is engaged under the tongue 90 and the tongue raised sufficiently to permit engagement between the thumb and finger so that the tear flap may be torn along the lines of perforations to effect removal of the pour opening closure and provide a smooth edged opening as shown in Fig. 6.

From the foregoing it is obvious that the container is of simple and inexpensive construction and may be furnished to the small dairy or other packager of liquids at small cost and which may be filled and sealed with simple and inexpensive equipment. It is also obvious that the container is more convenient in that the tear flap is easy

to operate and when opened exposes a pour opening having smooth, clean edges and provided with surrounding areas that have been protected against contact by the tear flap.

5 While the container is particularly described as formed of paper-like material, it is obvious that it may be formed of heat sealing plastic or plastic capable of being retained in shape and sealed by a solvent material. It is also obvious 10 that if the container is formed of a heat sealing plastic the vertical seam may be formed by applying heat to the areas which have been described as being secured by an adhesive.

What I claim and desire to secure by Letters 15 Patent is:

1. A container of the character described including a tubular body formed of a sheet like blank having underlapping and overlapping ends to form a side seam of increasing width from the 20 bottom toward the top of said body to provide a relatively wide lap across the top of said body and a relatively narrow lap at the bottom of said body, said underlapped end having a pour opening within the relatively wide upper portion of 25 the side seam and spaced inwardly from edges of said ends, said overlapped end having an edge face forming a substantially right angle with the surface of the underlapped end and having transverse lines of perforations extending from 30 said edge face inwardly of said overlap at the upper and lower sides of the pour opening to termination points inset from a corresponding edge of the underlap to provide a transverse tear flap in the overlap in covering relation with the 35 pour opening, adhesive between the overlap and underlap for closing said side seam, said adhesive being spaced below the lower line of perforation and above the upper line of perforation and completely securing the underlap along the entire 40 edge thereof and said adhesive securing the overlap to the underlap along the entire edge thereof with the exception of the space between said lines of perforations thereby providing a finger 45 engaging portion for said tear flap at said edge face of the overlapped end, and said adhesive including a relatively narrow stripe portion spaced inwardly of said edge face to complete a seal completely surrounding the pour opening while leaving an unattached tab portion between 50 the finger engaging portion and said narrow stripe of said adhesive.

2. A container of the character described including a tubular body formed of a sheet like blank having underlapping and overlapping ends to form edge faces at substantially right angles to the surfaces of said body and to form a vertical side seam of increasing width from the bottom 55 toward the top of said body to provide a relatively wide lap across the top of said body and a relatively narrow lap at the bottom of said body, said underlap having a pour opening defined within the relatively wide upper portion of 60 the side seam by a cut through the sheet like blank and spaced inwardly from the edge faces of said ends, said overlap having transverse lines of perforations extending inwardly from the edge face of said overlap at the upper and lower sides of the pour opening to a termination point inset from the edge face of the underlap to provide a transverse tear flap in the overlap in covering 65 relation with the pour opening, adhesive between the overlap and underlap for closing said side seam, said adhesive being spaced below the lower line of perforation and above the upper line of perforation and completely securing the under-

lap along the entire length thereof and said adhesive securing the overlap to the underlap along the entire edge thereof with the exception of the space between said lines of perforations to provide a finger engaging portion at said edge face of the overlapped end, said adhesive including a relatively narrow stripe portion intermediate said finger engaging portion and the pour opening to complete a seal completely surrounding the pour opening while leaving said edge face at the finger engaging portion free, and said adhesive securing the portion of the sheet like blank within said cut to the tear flap for removal of said portion upon pulling open of the tear flap.
